VERTICAL TURRET LATHE

Edward C. Bullard, Southport, and Claude M. Grinage,
Stratford, Conn.

Application April 15, 1955, Serial No. 35,525

Term of patent 14 years

(Cl. D54—6)

FIG. 1

FIG. 2

FIG. 4

FIG. 3

Fig. 1 is a top plan view of a vertical turret lathe to which the design of this invention has been applied.

Fig. 2 is a front elevational view of a vertical turret lathe to which the design of this invention has been applied.

Fig. 3 is a left-hand end elevational view of the vertical turret lathe shown in Figs. 1 and 2 and to which the design of this invention has been applied.

Fig. 4 is a right-hand end elevational view of the vertical turret lathe of Figs. 1 and 2 and to which the design of this invention has been applied.

We claim:

The ornamental design for a vertical turret lathe, as shown.
